BOTTLE CAPPER

Filed Sept. 2, 1931

UNITED STATES PATENT OFFICE

1,932,414

BOTTLE CAPPER

Harry J. Lebherz, Frederick, Md., assignor to The Everedy Company, Frederick, Md., a corporation of Maryland

Application September 2, 1931. Serial No. 560,841

6 Claims. (Cl. 226—84)

My invention relates broadly to bottle cappers and more particularly to a simplified construction of bottle capper capable of inexpensive assembly on a quantity production basis.

5 One of the objects of my invention is to provide an improved construction of bottle capper having parts which may be inexpensively manufactured on a quantity production basis and assembled with a minimum number of operations 10 for providing a tool of greater strength than has heretofore been obtainable.

Another object of my invention is to provide a construction of bottle capping tool having a cast base portion and a cast head portion with a 15 pressed metal standard interconnecting the base and head portions, the pressed metal standard having a cross-section substantially in the shape of an arch for imparting relatively great rigidity and strength to the standard.

20 Still another object of my invention is to provide a construction of bottle capping tool wherein in a cast base and a cast head portion are interconnected by a pressed metal channel shaped member arranged to have considerable inherent 25 rigidity and curved to position the head portion of the tool in a position centrally aligned over the base portion of the tool.

Other and further objects of my invention reside in a simplified construction of bottle capping tool as set forth more fully in the specification hereinafter following by reference to the 30 accompanying drawing, in which:

Figure 1 is a side elevation of the assembled bottle capping tool of my invention; Fig. 2 is an end view of the bottle capping tool of my 35 invention; Fig. 3 is a lateral cross-sectional view taken through the bottle capping tool adjacent the base portion thereof on line 3—3 of Fig. 1; Fig. 4 is a lateral cross-sectional view taken 40 through the standard of the bottle capping tool on line 4—4 of Fig. 1; Fig. 5 is a view showing the relative arrangement of the parts of the bottle capping tool prior to an assembly operation; and Fig. 6 is a cross-sectional view taken through 45 the standard on line 6—6 of Fig. 5.

My invention is directed to a simplified construction of bottle capping tool in which a pressed metal standard is provided for interconnecting a cast base portion and a cast head portion. The 50 pressed metal standard has a substantially arch shaped cross-section and is curved from a vertical position adjacent the base portion to a position in which the head portion is aligned vertically over the base portion. The head portion includes a mounting means for an actuating gear

and a ram which may be reciprocated along a vertical axis under control of the actuating gear. The pressed metal standard is apertured with rivet holes adjacent opposite ends thereof, which holes align with holes provided in the cast base 60 portion and the cast head portion for permitting rivets to be driven through the standard for securing the standard in position with respect to the base portion and the head portion. By reason of the arch shaped construction of the standard, considerable rigidity is imparted to the standard and substantial strength secured in the curved portion of the standard which forms the back-bone of the bottle capper for insuring proper operation of the tool under conditions of stress 65 and strain.

Referring to the drawing in detail, reference character 1 designates a cast metal base having an upstanding guard portion 2 and a cast lug portion 3. The base portion 1 has a pad or rest 75 4 secured thereto on which a bottle which is to be crowned is supported. The lug 3 on the cast base 1 is provided with apertures 3a for receiving rivets which are employed in establishing a rigid connection between the standard 5 and the base 1. 80 The standard 5 has rivet holes 5c adjacent the lower end thereof which are spaced in accurate alignment to the apertures 3a in lug 3 for receiving the rivets 6 which are passed therethrough for insuring a rigid connection between the 85 standard and the base. The standard 5 is pressed from sheet metal in a substantially arched or channel shaped cross-section as illustrated in Fig. 6, the edges of the standard extending outwardly from the channel shaped portion of the 90 standard along curves as represented at 5a and 5b, which are tangent to the lines disposed at acute angles with respect to the central axis of the standard as shown in Fig. 6. The edges 5a and 5b are flared outwardly from the side walls 95 of the channel 5 and serve to impart the required strength to the standard under conditions of stress and strain during operation of the bottle capping tool. The channel shaped standard 5 is curved at the upper portion thereof as indicated at 5d in order to insure the mounting of the cast head 7 in a position directly over the base 1. The upper portion 5d of the standard is provided with rivet holes 5e disposed in predetermined spaced relation as shown. The cast metal 100 head 7 is provided with a lug portion 8 terminating in a flanged edge 8b and a flanged abutment 8c. The flanged edge 8b is adapted to fit rigidly against the outwardly flared portions 5a and 5b of the channel shaped standard 5. The abutting 105 110

flanges 8c form a stop against the upper edge of the channel shaped member 5 designated at 5f. The lug 3 is apertured at 8a for receiving rivets 9 which extend through the apertures 5e in the upper portion of the standard 5. Rivets 9 are passed through the aligned apertures and secured in position in the same manner that rivets 6 are secured in position between the lug 3 and the end of the channel shaped standard 5. The cast head 7 is provided with a laterally extending housing 11 which has a bore therein for receiving the actuating gear 18 which is operated by movement of the hand lever 12 from handle 14.

The cast head 7 has a vertically extending bore portion 10 connected therewith through which the ram 15 passes. Ram 15 has rack teeth 17 cut on one side thereof meshing with the teeth on gear 18. A bottle capping throat 16 is supported on the end of ram 15 and is adapted to be pressed downwardly over the crown cap of a bottle for crimping the cap in position. The bottle capping throat 16 is preferably of the double seal type as set forth more fully in my Letters Patent No. 1,421,698, dated July 4, 1922.

I have found that the manufacture of bottle capper tools employing the U channel or beam as a supporting post is a considerable improvement over various forms of cast standards heretofore employed and which were subject to breakage during shipment and use. The U or arch shaped channel constituting the standard of the bottle capper tool of my invention is not subject to breakage because of its inherent rigidity. The operations necessary to rivet the cast metal base to one end of the standard and the cast metal head to the other end of the standard are very simple and may be performed expeditiously. The cost of the materials forming the bottle capping tool of my invention are substantially less than materials heretofore required in the construction of a bottle capper, and the labor in assembling the parts is substantially less, at the same time that an improved product is manufactured.

Various forms of spring lift mechanisms may be applied to the ram and hand operating lever but for purposes of illustrating my invention these refinements have been omitted.

While I have described my invention in one of its preferred embodiments I desire that it be understood that modifications in the form and construction of the bottle capper of my invention may be made within the scope of the appended claims without departing from my invention.

What I claim as new and desire to secure by Letters Patent of the United States is as follows:

1. A bottle capper comprising a cast base portion, an upstanding lug on said base portion, a cast head portion, a depending lug on said head portion and a pressed metal standard interconnecting the lugs on said base and head portions, a substantially semi-circular guide connected with said base portion for locating a bottle adjacent said standard, and means carried by said head portion for successively applying crown caps to bottles positioned on said base portion.

2. A bottle capper comprising a cast base portion having a vertically extending lug connected therewith, a cast head portion having a vertically disposed lug depending therefrom, limiting stops formed integrally with each of said lugs and a pressed metal standard connected at opposite ends and abutting at its opposite ends with said limiting stops with opposite sides of said lugs, said

head portion carrying means thereon for successively applying crown caps to bottles supported on said base portion.

3. A bottle capping tool comprising a cast base portion having a vertically extending lug integrally connected therewith, a cast head portion having a lug depending therefrom, shoulders formed on opposite sides of said lugs and a channel shaped pressed metal standard having its opposite ends abutting with said shoulders and enveloping said lugs and riveted thereto a substantially semi-circular guide connected with said base portion for locating a bottle thereon adjacent said standard, and means carried by said cast head portion and disposed directly over said cast base portion for successively applying crown caps to bottles supported on said base portion.

4. A bottle capping tool comprising a cast base having an upwardly extending end wall portion, a vertically extending lug integrally connected with said wall portion, a cast head having a depending lug thereon and carrying abutting flanges thereon extending at an angle to each other and a pressed metal standard connected at opposite ends of said lugs, said standard having the edges thereof flared outwardly in abutment with the curved wall on said base and the angularly disposed flanges on said head, and means carried by said head for successively applying crown caps to bottles supported on said base.

5. A bottle capper comprising a cast base portion having a circular end wall, a lug integrally connected with said end wall and extending rearwardly therefrom, a cast head, a lug depending from said cast head, said lug having flanges thereon extending normal to each other, a pressed metal channel having outwardly flared edge portions and a curved top portion, the top of said channel being riveted to said head with the outwardly flared edges thereof and the extremity thereof in abutment with the flanges on said head, the lower end of said pressed metal channel being riveted to the lug on said base portion and having its outwardly flared edges abutting with the circular wall of said base portion, and means carried by said head centrally over said base portion for successively applying crown caps to bottles supported on said base portion.

6. A bottle capper comprising a cast base portion having a circular end wall, a lug integrally connected with said end wall and extending rearwardly therefrom, a cast head, a lug depending from said cast head, said lug having flanges thereon extending normal to each other, a pressed metal channel having outwardly flared edge portions to which lines drawn tangent thereto are disposed at acute angles with respect to the central axis of said pressed metal channel, said channel having a curved top portion, the top of said channel being riveted to said head with the outwardly flared edges thereof and the extremity thereof in abutment with the flanges on said head, the lower end of said pressed metal channel being riveted to the lug on said base portion and having its outwardly flared edges abutting with the circular wall of said base portion, and means carried by said head centrally over said base portion for successively applying crown caps to bottles supported on said base portion.

HARRY J. LEBHERZ.
